UNITED STATES PATENT OFFICE.

RAYMOND L. CONNIF, OF IRONWOOD, MICHIGAN.

METALLIC WINDOW-FRAME AND SASH CONSTRUCTION.

Application filed April 13, 1927. Serial No. 183,498.

This invention relates to metallic window construction adapted to provide a strong support with a remainder of a building structure.

Another object of the invention comprehends grooves in the sashes and jambs.

A further object contemplates keys carried within the grooves to slidably mount the sashes and seal the same from weather conditions.

10 An additional object consists of additional grooves in the jambs within which the side rails of screens may be mounted.

With the above and other objects in view, the invention further consists of the following novel features and details of construction to be hereinafter more fully described, illustrated in the accompanying drawings and pointed out in the appended claim.

In the drawings:

20 Figure 1 is a front elevation of the frame and sashes mounted therein.

Figure 2 is a vertical sectional view taken through the frame.

Figure 3 is a transverse section taken on line 3—3 of Figure 1.

Figure 4 is a detail section taken through a portion of the jamb and sash and illustrating the relative arrangement of the keys.

Figure 5 is a perspective of a key.

30 Referring to the drawings in detail, wherein like characters of reference denote corresponding parts, the reference character 10 indicates a window frame constructed of metal. The sill 11 after the manner of the top of the frame is provided with fins 12 extended longitudinally thereof. The jambs 13 of the window frame are provided with spaced vertically disposed grooves 14 registering with grooves 15 in the side rails of the sashes 16.

40 The sashes are also constructed of metal. Keys 17 are positioned within the registering grooves 14 and 15 of the jambs and sashes and held against displacement within the grooves of the sashes by bolts 18. Such arrangement will permit the sashes to be slid within the frame. The keys 17 combine the results of a sliding mounting and weather strip for the sashes.

The top and bottom rails of the upper and lower sashes respectively are provided with 50 grooves 19 to receive the fins 12 whereby the perimeter of the sash is sealed from outside atmospheric conditions.

The meeting rails of the upper and lower sashes are provided with grooves 20 and ribs 55 21 adapted for interfitting engagement to seal the connection between the sashes. Such construction will entirely weather strip the whole assembly.

In Figure 1 of the drawings I have illustrated in a dotted line position a key in the act of being driven or otherwise slid within the grooves precedent to anchorage upon a sash through the instrumentality of the bolts 18 which may be of a varied character incident 65 to the finish or design of the particular window sash.

Each of the sashes is provided with an annular rib 22 upon the inner sides of the rails thereof against which transparent panels 23 70 may repose when held against displacement thereon by putty or other plastic composition as illustrated at 24.

The invention is susceptible of various changes in its form, proportions and minor 75 details of construction, and the right is herein reserved to make such changes as properly fall within the scope of the appended claim.

Having described the invention, what is claimed is:

80 A window construction comprising a frame provided with grooves in the sides thereof and ribs at the top and bottom, sashes carried within the frame having grooves in the side rails thereof adapted for registration with the 85 aforementioned grooves, additional grooves provided in the outermost rails of the sashes adapted to receive the ribs at the top and bottom walls of the frame, and keys carried within the sash grooves and projected outwardly therefrom within the grooves in the sides of the frame to slidably mount the sashes therein.

90 In testimony whereof I affix my signature.

RAYMOND L. CONNIF.
